Fig. 12.

INVENTOR,
B.L. Montague,
BY
Albert E. Dietrich,
ATTORNEY.

mounted on shaft 21 in line with the troughs 31. The troughs 31 are provided with wear plates 35 similarly to those 12 of the troughs 11.

Bearing head supports 40 are attached to the upper ends of the troughs 31 and carry adjustable bearings 41 for the conveyor shaft 42 on which sprockets 43 are mounted to line up with the troughs 34 and sprockets 33. Chains having log pushers pass around the sprockets 33-43 with their upper flights running in the troughs 34.

The pushers comprise certain links 52 on which are carried the upright fingers 49 whose free ends are preferably bent or curved in a forward direction as at 48, the fingers being braced by side braces 51 and a center brace 50 as shown best in Figs. 9 and 10.

The free end of the upper conveyor is provided with a head shaft guard composed of curved side bars 44 and a cross bar 45 (see Figs. 3 and 5).

A hydraulic lift includes a cylinder 67 and a piston whose rod 68 is pivoted to the shaft 39, the cylinder being pivoted on the pin 29 (see Fig. 2).

In Fig. 11 is shown the floor plan of the power plant, by reference to which it will be seen that a floor plate 53 is mounted on the channel irons 1 (welded or otherwise secured). On this floor 53 is mounted a suitable engine 54, having a flywheel 54^a and whose shaft 54^x carries a triple groove pulley 54^v.

Mounted in bearings 60 is a shaft 56 on which runs a clutch pulley 55 that is driven from pulley 54^v by belts 57. A shiftable clutch element 58 is suitably keyed to the shaft 56 and may be brought into and out of engagement with the clutch element 55^a of the clutch pulley by means of a lever 59. As the construction of the clutch device is well known and per se is not of my invention further description of the same is unnecessary.

The shaft 56, via a sprocket and chain connection 63 drives a shaft 61 that is mounted in bearings 62 and has a sprocket 64 around which and the sprocket 66 a conveyor driving chain 65 passes.

On a suitable support 69 a pressure pump 70 is mounted and driven via belt 72 and pulleys 54^v, 71 by the motor or engine 54.

Referring now to Fig. 12 it will be seen the hydraulic system for raising and lowering the conveyor includes an oil tank 73, a control valve 74, a pressure pump 70, a pipe from tank 73 to the L. P. side of valve 74, a pipe 76 from pipe 75 to the top of cylinder 67, a pipe 79 from the L. P. side of the pump 70 to tank 73, a pipe 77 from the H. P. side of the pump 70 to the H. P. inlet side of control valve 74 and a pipe 78 from the H. P. outlet side of control valve 74 to the lower end of the cylinder 67. The specific hydraulic lift system may be of any approved type and per se is not claimed in this application.

In operation logs L (Fig. 1) are placed on the lower conveyor and carried up to the upper conveyor where the logs are taken up by the pushers of the upper conveyor and discharged over the guard 44 onto the truck or other place of deposit.

As the logs pile up at the place of delivery 70 the free end of the upper conveyor is raised accordingly. If the weight of the mechanism to the right of wheels 27 in Fig. 1 is insufficient to overbalance the weight of the conveyor and its load to the left of the wheels 27 a suitable amount

of sand, dirt, gravel, rock or water is placed in the ballast box on the ground.

From the foregoing it will be seen that I have provided a very simple, strong, easily manipulated loader for the desired purposes and I wish it understood that changes in the construction of the parts may be made within the scope of the appended claims without departing from the invention.

10. What I claim is:

1. In a loader of the class described, a two-wheeled truck, a two stage elevator mounted on said truck, one stage of said elevator lying to one side of the axis of the truck wheels, the other 15 stage of said elevator lying in major part to the other side of said axis, the second stage of said elevator being substantially longer than the first stage, said elevator stages having a conveyor shaft in common, means to apply driving power 20 to said common shaft, and means for overbalancing the weight of the second stage and its load on the wheel axis as a pivot.

2. In a loader of the class described, a truck frame, an axle carrying two wheels for supporting one end of said frame, the other end of said frame being constructed to rest on the ground when the loader is in use, an endless chain conveyor fixedly mounted on said frame and inclined upwardly from the ground-engaging end of the 30 frame toward the wheeled end of the same, a second endless chain conveyor one end of which is pivotally mounted at the upper end of the first mentioned endless chain conveyor and extending beyond the wheeled end of said frame, said conveyors having a conveyor driving shaft in common, means to apply driving power to said common driving shaft, hydraulic means carried by said frame and operatively connected to said second endless chain conveyor for raising and lowering 35 the same, and a towing bar connected to the ground-engaging end of said frame.

3. In a loader of the class described, a truck including a frame unit composed of side longitudinal channel irons and cross beams, upwardly 45 inclined beams extending upwardly from one end of said channel irons toward the other end thereof, conveyor troughs mounted on said upwardly inclined beams, bearing head supports secured at each end of said inclined beams, a brace connecting said upwardly inclined beams and said side longitudinal channel irons, ballast-box plates connecting the lower bearing head supports and constituting therewith a ballast box, a wheeled axle supporting one end of said truck, bearing 50 heads on said bearing head supports; conveyor shafts mounted in said supports and having sprockets, endless chains passing about said sprockets and having pushers; a second endless chain conveyor one end of which is connected 55 pivotally to the higher of said conveyor shafts and overhanging said truck frame; means on said truck frame for raising and lowering said conveyor; means on said truck frame for driving both conveyors; and a tow bar by which 60 said truck frame may be pulled from place to place.

4. In a loader of the class described, a truck including a frame unit composed of side longitudinal channel irons and cross beams, upwardly 65 inclined beams extending upwardly from one end of said channel irons toward the other end thereof, conveyor troughs mounted on said upwardly inclined beams, bearing head supports secured at each end of said inclined beams, a brace connecting said upwardly inclined beams and said

side longitudinal channel irons, ballast-box plates connecting the lower bearing head supports and constituting therewith a ballast box, a motor guard frame secured to said side channel irons and to said brace, a top plate on said motor guard frame, and a shield plate secured to and between said upwardly inclined beams, a wheeled axle supporting one end of said truck, bearing heads on said bearing head supports; conveyor shafts mounted in said supports and having sprockets, endless chains passing about said sprockets and having pushers; a second endless chain conveyor one end of which is connected pivotally to the higher of said conveyor shafts and overhanging said truck frame; means on said truck frame for raising and lowering said second conveyor; means on said truck frame for driving both conveyors; and a tow bar by which said truck frame may be pulled from place to place.

5. A loader according to claim 4 wherein the conveyor-driving means includes a motor and power transmitting mechanism located beneath said top plate and said shield plate.

6. In a loader of the class described wherein is provided a portable truck comprising a frame, a two wheeled axle supporting one end of said frame, a second support for the other end of the frame, and a power plant on said frame; a lower conveyor mounted on said frame and extending from said second support upwardly to a place above the frame adjacent to but short of a vertical plane passing through the wheeled axle, said conveyor including a lower axle and an upper axle, sprockets on said last two axles and endless chains connecting the upper and lower axles' sprockets; a second conveyor comprising a frame pivoted to the upper axle of the first

mentioned conveyor, a third axle at the free end of the second conveyor frame, sprockets on said third axle and one the upper axle of the first mentioned conveyor frame, sprocket chains connecting the sprockets for said second conveyor, all said chains having fingers at predetermined intervals along the lengths of the chains; a driving connection from the power plant directly to the common shaft of said conveyors; and means on the truck and connected to said second conveyor for raising and lowering the free end of the same.

BERT L. MONTAGUE.
